ABSTRACT: Mechanism for controlling the rotational let-off speed of a yarn supply bobbin to maintain substantially constant tension of the yarn used in fabricating machines such as spiral winders and the like. The tension-controlling means includes reader means for reading the diameter of the yarn supply which acts through resilient means between the reader means and brake means to control the rotation speed of the yarn supply in accordance with the diameter of the yarn supply.

YARN-TENSIONING MEANS FOR SPIRAL WINDING MACHINES

BACKGROUND OF THE INVENTION

Heretofore, in yarn-fabricating machines in which the yarn supply was rotated by the yarn as it was withdrawn from the supply and fabricated by the machine tension was applied to the yarn by applying a braking force on the yarn supply bobbin. The braking force applied to the bobbin was usually constant but since the leverage exerted by the yarn to turn the bobbin varied as the supply of yarn was depleted, the tension in the yarn also varied.

In efforts to provide a more uniform tension in yarn when the yarn was used to rotate the yarn supply as it was withdrawn therefrom by fabricating means mechanism was provided to control the rotation of the yarn supply such as that shown in U.S. Pats. Nos. 2,395,807 and 2,397,663. As shown in these patents the means for controlling the yarn tension, which means were associated with the warp beams of warp-knitting machines, included a pair of brakeshoes acting on the beam, a spring or springs connected between the brakeshoes, a feeler member which was biased into engagement with the windings of the yarn on the beam by a spring and connections between the feeler member and brakeshoes for varying the force applied by the spring connecting the brakeshoes to vary their braking force on the beam in accordance with the diameter of yarn supply on the beam. While this mechanism was designed to control the yarn tension by controlling the rotation of the yarn beam in accordance with the diameter of the yarn on the beam the mechanism was both cumbersome and expensive. Furthermore, the number of springs required made it difficult to control the rotational speed of the beam and the tension in the yarn with the degree of accuracy required.

The instant invention has for its principle object the provision of means for controlling the tension in yarn or a strand of material withdrawn from a strand supply rotatable by the strand and used in a fabricating machine such as a spiral winder or the like, the tension-controlling means including spring-controlled means for applying braking force to the strand supply, and means for reading the diameter of the strand in the supply, said last-named means being adapted to vary the force of spring-controlled means and the force applied thereby to the strand supply in a manner to maintain a substantially uniform tension in the strand as the strand in the supply is reduced from full to depleted condition.

SUMMARY OF THE INVENTION

Briefly summarized the invention resides in the provision of means for controlling the tension in yarn or a strand withdrawn from a rotatable supply as it is used in a fabricating machine such as a spiral winder and the like, the tension-controlling means including a reader means for reading the diameter of the supply, a brake lever acting on the yarn supply to resist rotation thereof and a spring between the reader means and brake lever. The force of the spring is gradually reduced to reduce the braking force of the brake lever on the yarn supply by the reader means as the diameter of the yarn or strand in the supply is reduced between full and depleted limits.

BRIEF DESCRIPTION OF THE DRAWINGS

FIG. 1 is an elevational view of one deck of a machine for spirally winding yarn on a core with strand supply and tensioning fixtures according to the invention incorporated therein;

FIG. 2 is a view of the machine as seen from the left of FIG. 1;

FIG. 3 is an elevational view on an enlarged scale of one of the yarn supply fixtures shown in FIG. 1;

FIG. 4 is a partial plan view of FIG. 3;

FIG. 5 is a view partly in plan and partly in cross section taken substantially on the line and in the direction of the arrows 4-4 of FIG. 3;

FIG. 6 is a cross-sectional view taken on the line and in the direction of the arrows 6-6 of FIG. 4;

FIG. 7 is a cross-sectional view taken on the line and in the direction of the arrows 7-7 of FIG. 4; and

FIG. 8 is a detail view of a portion of the mechanism of FIG. 3.

Referring to FIGS. 1 and 2 of the drawings there is shown one of the winding decks or heads 10 of a machine for forming reinforced hose and the like including a base member 11, vertical plates 12 and 15 supported on the base member and forming a fixed portion of the deck in which the operating means is carried for a rotary member 16. The rotary member 16 carries a plurality of like fixtures 17 each of which is adapted to supply and tension a yarn 20 directed to a collector

10 or guide ring 21 where the yarn is spirally wound on a core or mandrel 22 moving axially through the guide ring. Except for the fixtures 17 the construction and operation of the head 10 is conventional and forms no part of the instant invention.

The fixtures 17 each include a base 25 having a bushing 26 (see FIGS. 3 and 6), the base being secured to the rotary member 16 between an enlarged head 27 at one end of the bushing and a nut 30 threadably carried on the other end of the bushing for engagement with the underside of the rotary member.

Secured in a bore 31 in the bushing 26 as by pin 32 is one end 35 of a shaft or spindle 36. The spindle 36 has a bearing portion 37 for mounting the inner race of a ball bearing 40. Mounted on the outer race of the bearing 40 is an enlarged lower annular portion 42 of a sleeve 45. The upper end of the sleeve 45 is bored to receive the outer race of a ball bearing 46.

46. The inner race of the ball bearing 46 is mounted on a reduced upper end portion 47 of the spindle 36 between a shoulder 50 on the spindle and a C-ring 51 carried in a groove in the portion 47. The sleeve 45 is retained against axial movement on the outer races of bearings 40 and 46 by shoulders 52 and 55, respectively, formed in the sleeve. The sleeve 45 which is adapted to receive the yarn bobbin 56 is provided with raised spirally extending ribs 57 (FIGS. 5, 6 and 8) for engagement with the inner bore of the bobbin to prevent relative rotation between the bobbin and sleeve.

Rotation of the bobbin 56 on the spindle 36 of the fixture 17 is controlled to apply tension on the yarn 20 as it is withdrawn from the bobbin and wound on the core 22. For this purpose the outer periphery of portion 42 of the spindle is adapted to be engaged by a brakeshoe 60 (see FIGS. 3 and 5), of leather or the like, secured by adhesive to a brake lever 61 pivotally mounted on a stud 62 carried in the base 25 for movement in a plane parallel to the plane of the base. An arm 65 of the brake lever 61 is connected by a coil-type tension spring 66 to a nut

50 67 forming a part of a reader means 68 for reading the diameter of the yarn supply on the bobbin 56. The nut 67 is carried on a threaded spindle 70 mounted for rotation in ears 71 projecting from one arm 72 of a lever 75 pivoted on a stud 76 carried in a portion 77 of the base 25 (FIGS. 3, 4 and 5). Thumb nuts 80 are provided on opposite ends of the spindle 70 by means of which the spindle may be rotated to manually adjust the position of the nut 67 thereon in preparation for operation to vary the tension in spring 66 and the braking force applied by the brake lever 61 to the sleeve 45 as may be required by

60 the particular yarn employed or other conditions present. The lever 75 is provided with a second arm 81 having an open-ended slot 82 for receiving one arm 85 of a lever 86 pivotally mounted on a pin 87 carried in the portion 77 of the base 25 (FIGS. 3 and 7). The lever 86 has a second arm 90 with an arcuate feeler surface 91 adapted to read the outer diameter of the yarn windings on the bobbin 56 through a flexible strip 92, of plastic material such as Teflon or the like, secured by screws 93 to a post 96 carried in the base 25 (FIGS. 3, 4 and 7). The spring 66 connected between the arm 65 of the brake lever 61 and the nut 67 on the lever 75 tends to turn the lever clockwise about the stud 76 and to turn the lever 86 counterclockwise, as viewed in FIG. 7 to maintain the surface 91 of arm 90 in engagement with strip 92, and the latter in engagement with the yarn on the bobbin, and to turn the brake lever 61 counterclockwise as viewed in FIG. 5, to main-

tain the brakeshoe 60 in braking engagement with the portion 42 of the sleeve 45.

As will be understood, in the absence of a braking mechanism as provided by the instant invention, when the bobbin has a full supply of yarn the pull on the yarn to turn the bobbin would be at its minimum and as the diameter of the supply decreases the required pull would correspondingly increase. The relationship between the brake lever 61 and the levers 75 and 86 of the reader means 68 is such that when the bobbin 45 has a full supply of yarn the braking force exerted by the reader means through the spring 66 and the brake lever 61 on the sleeve 45 is at its maximum to provide the required tension in the yarn at the fabricating point. Thereafter as the diameter of the windings of yarn is gradually reduced the levers 75 and 86 of the reader means 68 are moved to gradually reduce the braking force applied through the spring 66 and brake lever on the sleeve to thereby maintain a substantially uniform tension in the yarn between the full and depleted limits of the yarn supply.

It will be understood that the improvement specifically shown and described by which the above results are obtained can be changed and modified in various ways without departing from the invention herein disclosed.

We claim:

1. In a machine for spirally winding a strand onto a core member, said machine having rotatable means for supporting a wound supply from which said strand is withdrawn as it is wound onto said core, and means for controlling the tension in said strand withdrawn from said supply including a brake lever for applying brake force to said rotatable supporting means, reader means for engaging and reading the diameter of the supply of said strand, and resilient means interconnecting said brake lever and said reader means to bias said brake lever in a braking condition with said rotatable supporting means and said reader means in reading engagement with the supply of said strand, said reader means acting through said resilient means to vary the braking force applied to said rotatable supporting means by said brake lever in accordance with the diameter of the supply of said strand.

2. A machine according to claim 1 in which said resilient means comprises a spring.

3. A machine according to claim 1 in which reader means includes a first lever for engaging said supply of said strand, and a second lever movable by said first lever in accordance with the diameter of said supply of said strand, and said resilient means interconnects said brake lever and said second lever of said reader means.

4. In a machine for spirally winding yarn onto a core member, said machine having rotatable means for supporting a supply from which said yarn is withdrawn as it is wound onto said core, and means for controlling the tension in said yarn withdrawn from said supply including a brake lever for engaging said rotatable supporting means, reader means for engaging and reading the diameter of the supply of yarn, and resilient means interconnecting said brake lever and said reader means to maintain said brake lever in engagement with said rotatable supporting means and said reader means in reading engagement with said supply of yarn, said reader means acting through said resilient means to vary the braking force applied to said rotatable supporting means by said brake lever in accordance with the diameter of said supply of yarn, said reader means includes a first lever for engaging said supply of yarn, and a second lever movable by said first lever in accordance with the diameter of said supply of yarn and said resilient means comprises a spring, said spring interconnecting said brake lever and said second lever of said reader means, further comprising means on said second lever of said reader means for adjusting the force of said spring interconnecting said brake lever and said second lever of said reader means.

5. A machine according to claim 4 in which said adjusting means for said spring on said second lever of said reader means includes a member on said second lever for engaging one end of said spring and there is means for adjusting the position of said member on said second lever.

6. A machine according to claim 5 in which said means for adjusting the position of said member on said second lever comprises a threaded spindle on which said member is mounted, said threaded spindle being rotatably mounted on said second lever to adjust the position of said member on said second lever.
